E. D. FALES

MEASURED SERVICE TELEPHONE SYSTEM

Filed June 14, 1919

Inventor
Edward D. Fales

UNITED STATES PATENT OFFICE.

EDWARD D. FALES, OF WESTERN SPRINGS, ILLINOIS, ASSIGNOR TO AUTOMATIC ELECTRIC COMPANY, OF CHICAGO, ILLINOIS, A CORPORATION OF ILLINOIS.

MEASURED-SERVICE TELEPHONE SYSTEM.

Application filed June 14, 1919. Serial No. 304,206.

To all whom it may concern:

Be it known that I, EDWARD D. FALES, a citizen of the United States of America, and a resident of Western Springs, in the county of Cook and State of Illinois, have invented certain new and useful Improvements in Measured-Service Telephone Systems, of which the following is a specification.

- 10 My invention relates in general to an improved means for controlling a measured service or toll assessing device and more specifically to improved circuit arrangements for automatically controlling a coin collecting device such as that shown in United States Letters Patent No. 1,043,219, granted November 5, 1912 to O. F. Forsberg, when used in an automatic telephone system.
- 20 Among the objects of my invention are to provide improved means for collecting a pre-deposited coin immediately upon the response of a called subscriber and for refunding the coin to a called subscriber if 25 the call is not successful, when the calling party hangs up, by means of a pair of high voltage batteries of opposite polarity.

In the drawings I have shown a substation A equipped with a pay station device such as that shown in the above mentioned patent, having a line switch C individual thereto which is operated when the subscriber removes his receiver to automatically select an idle one of a plurality of connector switches (not shown). The connectors to which the switch C has access may be of any standard type, one of such connectors being shown in United States Letters Patent No. 1,269,245, granted

- 40 June 11, 1918 to Albert Andersen. This connector is arranged to reverse battery to the talking circuit on certain levels but does not reverse battery on other levels when the subscribers are of the class which 45 may be called free of charge. The group of relays E are for coin controlling purposes and may be inserted in the talking circuit leading to the connector switch or one or more selector switches of the type shown in 50 said last mentioned patent may be inserted between the switch C and the connector in which case the relays E will probably be inserted in the trunk leading to the selector. In any case the operation will be the same.

When the subscriber at A removes his receiver to initiate a call a circuit is completed for line relay 6 of the line switch C. Relay 6 prepares a series circuit for relay 7 and rotary magnet 8 at springs 12 and closes a circuit for magnet 8 direct to 60 private wiper 10, short circuiting relay 7 in case the first trunk is busy and ground is present on wiper 10. In this case magnet 8 operates as a buzzer to rotate the wipers 9, 10 and 11 over the contacts of its bank 65 until an idle trunk line is reached which has no ground on its test contact. At this time relay 7 being no longer shorted out, energizes to disconnect the relay 6 and ground from the line circuit and extends the 70 connection through to the seized trunk.

As stated, this trunk line is assumed to terminate in a connector switch having the usual line relay, one winding connected to the upper conductor and battery and the 75 other to the lower conductor and ground. Now when relay 7 energizes, a circuit is completed for the line relay of the connector which extends from battery through the upper winding, conductor 13, springs 14 80 and 15, upper winding of relay 16 and resistance 17 in parallel, winding of relay 18 and resistance 19 in parallel, springs 20, wiper 9, to and through line A, and back through wiper 11, springs 21 and 22, springs 85 24 and 25, and through the other winding of the line relay to ground. The line relay of the connector energizes over this circuit as does the relay 18. Relay 16 does not energize, it requiring the combined energy 90 of both windings in the same direction to attract its armatures but adapted to be held up by its lower winding alone.

The connector line relay closes the circuit of the usual release relay to open the release circuit and supply ground to the holding trunk 28 which ground passes to relay 7 of switch C to hold the same energized, and also to the lower winding of relay 16 to polarize said relay.

Relay 18, upon energizing, closes a circuit for relay 29 at springs 30 and 31 and opens one point at springs 30 and 32 in the circuit of relay 34. Relay 18 also shorts out a part of the resistance 19 and closes springs 35 105 which have no effect at this time. Relay 29 energizes to close another point in the circuit of relay 34.

The substation A, Fig. 1, is shown only diagrammatically with only the essential parts of the Forsberg coin collector which is non-responsive to the normal current in the line circuit and which responds to current from the high voltage battery B to deflect a deposited coin into the collect chute. This magnet also responds to the current from high voltage battery D to operate its armature in the opposite direction to deflect a deposited coin into the refund chute. When the coin is deposited it rests upon spring 3 pressing this spring into engagement with the spring 4 and forcing the springs 4 and 5 out of engagement. It will thus be seen that the short circuit is removed from the calling device and the magnet 2 is connected to the line circuit.

The calling subscriber now operates his calling device to control the connector switch to seize and signal the called subscriber. If the subscriber called is a pay line then the back bridge of the connector will be energized as soon as the called subscriber answers to reverse the flow of current in the talking circuit and over conductors 13 and 36. This reversal of current causes relay 16 to energize, as its two windings now assist each other, and close springs 37 to short out resistance 17 and also momentarily closes the springs 38, 39 and 40 into contact to momentarily close the circuit of slow relay 41. Relay 41 operates to open the talking circuit at springs 14 and 15 and at springs 24 and 25 and includes the high resistance bridge winding 42 across the line to hold the connector line relay energized. Relay 41 also closes springs 43 to momentarily connect the battery B to the calling line and to magnet 2. Current from battery B is of higher potential than the switch operating battery and is of such a direction as to cause magnet 2 to tilt its armature in one direction to deflect the coin into the collect chute and restore springs 3, 4 and 5 to normal.

As relay 41 is only energized momentarily the talking circuit will be open only for an instant and the subscribers may proceed with the conversation over the heavy conductors shown.

Assume now that the called subscriber had not answered or that a free line was called or that the party called was busy. In any case the battery to the calling line will not be reversed and therefore relay 16 will not be energized to connect battery B to the calling line. In such a case the coin remains suspended until the calling subscriber restores his receiver and opens the line circuit. When the line circuit is opened the line relay of the connector falls back to release the switch, and remove ground from the release trunk, however, relay 18 of the group E de-energizes also to open the circuit of relay 29 and relay 29 falls back to close a circuit

through springs 30 and 32, springs 33 which are closed momentarily, and relay 34 to battery. Relay 34 operates to connect direct ground to the release trunk and to hold ground on the polarized winding of relay 16. Of course, the ground to relay 16 has no effect, as that relay has not energized, but the ground to the switch C prevents that switch from releasing until the coin is refunded. A further result of the momentary energization of relay 34 is the opening of the line conductors at springs 20 and springs 21 and 22, and the connection of the battery D through the springs 23 and 21 to the coin collect magnet 2 at the substation. Current from the battery D is of such strength and direction as to cause relay 2 to operate to direct the coin into the refund chute where it may be recovered by the calling subscriber. Relay 34, of course, energizes only momentarily due to its circuit being opened at springs 33 of relay 29, and as soon as relay 34 deenergizes the switch C releases. It will be noticed that in case the called subscriber answers and operates relay 16 to collect the coin by means of relay 41 then springs 39 and 40 of relay 16 will be held open to prevent any further operation of relay 41 to collect the coin, and in such a case when the calling subscriber hangs up, the relay 34 will operate to connect battery D to the calling line for refunding the coin. As the coin has already been collected, however, the connection of battery D to the line circuit has no effect.

Having fully described and ascertained the features and aspects of my invention, what I consider to be new and desire to have protected by Letters Patent, will be pointed out in the appended claims.

What I claim as my invention is:

1. In a telephone system, a line, a coin collecting device for said line, a magnet for operating said device, an automatic switch for extending a talking circuit from the line to another line, a battery for operating and talking purposes, said magnet nonresponsive to said battery, a pair of higher voltage batteries, means operated by the called subscriber when he answers for connecting one of said batteries to said magnet to collect the coin, and means controlled solely by the calling subscriber for connecting the other battery to the magnet to refund the coin.

2. In a telephone system, a line, a coin collecting device for said line, a magnet for operating said device, an automatic switch for extending a talking circuit from the line to another line, a battery for operating and talking purposes, said magnet nonresponsive to said battery, a pair of higher voltage batteries, means operated by the called subscriber when he answers for connecting one of said batteries to said magnet to collect the coin, and means controlled solely by the call-

ing subscriber for connecting the other battery to the magnet to refund the coin when the connection is released.

3. In a telephone system, a line, a coin collecting device for said line, a magnet for operating said device, an automatic switch for extending a talking circuit from the line to another line, a battery for operating and talking purposes, said magnet nonresponsive to said battery, a pair of high voltage batteries, means operated by the called subscriber when he answers for connecting one of said batteries to said magnet to collect the coin, and means controlled solely by the calling subscriber for connecting the other battery to the magnet to refund the coin, said last means common to the lines.

4. In a telephone system, a line having a coin collecting device and a magnet for operating same, an automatic switch for the line operative to extend a talking circuit from the line to a called subscriber, a relay in the talking circuit controlled solely by the called subscriber for operating said magnet to collect the coin when the called man answers, and another relay in the talking circuit controlled solely by the calling subscriber for operating said magnet to refund a coin to the calling subscriber if the call is not successful.

5. In a telephone system, a line having a coin collecting device and a magnet for operating same, an automatic switch for the line operative to extend a talking circuit from the line to a called subscriber, a relay in the talking circuit controlled solely by the called subscriber for operating said magnet to collect the coin when the called man answers, and another relay in the talking circuit controlled solely by the calling subscriber for operating said magnet to refund a coin to the calling subscriber if the call is not successful, both of said relays controlling the magnet by an impulse of increased current.

6. In a telephone system, a line having a coin collecting device and a magnet for operating same, an automatic switch for the line operative to extend a talking circuit from the line to a called subscriber, a relay in the talking circuit controlled solely by the called subscriber for operating said magnet to collect the coin when the called man answers, and another relay in the talking circuit controlled solely by the calling subscriber for operating said magnet to refund a coin to the calling subscriber if the call is not successful, one relay controlling the magnet by an impulse of increased current of one polarity and the other by an impulse of increased current in the opposite direction.

7. In combination with a telephone system in which coin collectors are used to charge for calls, said collectors each having a mag-

net operable in two directions to refund or collect a coin, automatic progressively movable switches for building up connections between two lines, means for operating the magnet in the collector on the calling line by an impulse of increased current of one polarity at the time the called subscriber answers to collect the coin, and means responsive to the replacement of the receiver by the calling subscriber for operating the magnet by an impulse of increased current of another polarity to refund the coin.

8. In combination with a telephone system in which coin collectors are used to charge for calls, said collectors each having a magnet operable in two directions to refund or collect the coin, automatic progressively movable switches for building up connections between two lines, and means for operating the magnet in the collector on the calling line by an impulse of increased current of one polarity at the time the called subscriber answers to collect the coin and for operating the magnet by an impulse of increased current of another polarity to refund the coin when the calling subscriber hangs up, said last means common to a plurality of the subscribers' lines.

9. In a telephone system, a line having a coin collecting device and a magnet for operating same, an automatic switch for the line operative to extend a talking circuit from the line to a called subscriber, a relay in the talking circuit controlled solely by the called subscriber for operating said magnet to collect the coin when the called man answers, another relay in the talking circuit controlled solely by the calling subscriber for operating said magnet to refund a coin to the calling subscriber if the call is not successful, said first relay controlled by a reversal of current in the talking circuit to collect the coin, and the other relay controlled by the opening of the line circuit to refund the coin.

10. In a telephone system, a line having a coin collecting device and a magnet for operating same, an automatic switch for the line operative to extend a talking circuit from the line to a called subscriber, a relay in the talking circuit controlled solely by the called subscriber for operating said magnet to collect the coin when the called man answers, another relay in the talking circuit controlled solely by the calling subscriber for operating said magnet to refund a coin to the calling subscriber if the call is not successful, and means for opening the talking circuit between the calling and called subscribers when either relay operates to control the coin collecting device.

11. In a telephone system, a line having a coin collecting device and a magnet for operating same, an automatic switch for the line operative to extend a talking circuit

- from the line to a called subscriber, a relay in the talking circuit controlled solely by the called subscriber for operating said magnet to collect the coin when the called man answers, another relay in the talking circuit controlled solely by the calling subscriber for operating said magnet to refund a coin to the calling subscriber if the call is not successful, said first relay controlled by a reversal of current in the talking circuit to collect the coin, and the other relay controlled by the opening of the line circuit to refund the coin, and means for opening the talking circuit between the calling and called subscribers when either relay operates to control the coin collecting device.
12. In a telephone system, a line having a coin collecting device and a magnet for operating same, an automatic switch for the line operative to extend a talking circuit from the line to a called subscriber, a relay in the talking circuit controlled solely by the called subscriber for operating said magnet to collect the coin when the called man answers, and another relay in the talking circuit controlled solely by the calling subscriber for operating said magnet to refund a coin to the calling subscriber if the call is not successful, both of said relays controlling the magnets by an impulse of increased current, and means for opening the talking circuits between the calling and called subscribers when either relay operates to control the coin collecting device.
13. In a telephone system, a line, a coin collecting device therefor having an operating magnet, means for extending a connection from said line to another line, a pair of high voltage batteries, means for operating said magnet to collect a coin through the medium of one of said batteries, when the called subscriber answers, and means controlled solely by the calling subscriber for causing said magnet to refund coins through the medium of said other battery.
14. In a telephone system, a line, a coin controlled measured service device therefor having an operating magnet, a pair of high voltage batteries, means for extending a connection to a called subscriber, means controlled by the response of the called subscriber for collecting a coin through the medium of one of said batteries, and means controlled by the calling subscriber for always connecting the other battery to said magnet to refund the coin if it has not been collected.
15. In a telephone system, a line, a coin collector therefor having an operating magnet, means for extending a connection from said line to a called line, a battery of one voltage for controlling the operation of said means, a battery of higher voltage, and means controlled by the calling subscriber only for always connecting said high voltage battery to said magnet after each call to refund coins which have not been collected.

Signed by me at Chicago, Cook County, Illinois, this 10 day of June, 1919.

EDWARD D. FALES.
